UNITED STATES PATENT OFFICE

PAUL D. PHILLIPS, OF DES PLAINES, ILLINOIS, ASSIGNOR TO BENJAMIN ELECTRIC MFG. CO., OF DES PLAINES, ILLINOIS, A CORPORATION OF ILLINOIS

SHOW CASE LIGHTING FIXTURE

Application filed January 27, 1930. Serial No. 423,650.

This invention relates to a show case lighting fixture and has special reference to such a fixture having lamp sockets therein connected to a feed through circuit in which 5 sockets screw base lamps may be easily and quickly inserted by means of a simple swinging movement without requiring the usual screwing in operation.

An object of this invention is to provide 10 a continuous show case lighting fixture having a feed through circuit to which lamp sockets may be attached at spaced intervals and electrically connected to the lead wires without the necessity of breaking or cutting 15 the wires.

A further object of this invention is to provide a show case lighting fixture in which are attached lamp sockets having flared receiving openings so that lamps may be inserted therein by a simple swinging movement without the necessity of the usual screw threading operation.

A still further object is to provide a show case lighting fixture having a casing comprising an outer covering member and an inner reflector member spaced apart at the top so as to form a channel through which the lead wires run whereby the same are protected and concealed.

30 Further objects and advantages of the present invention will be more readily understood by reference to the following description together with the accompanying drawing in which latter:

35 Figure 1 is a face view of a show case fixture embodying my invention showing the lamps positioned in the sockets and held in place by spring clips;

40 Fig. 2 is a cross sectional view taken on the line 2—2 of Fig. 1 showing the side and bottom contacts of the socket in contact relation with the lamps;

45 Fig. 3 is a face view of the reflector member with the socket removed showing an insulation sheet placed over an opening in the reflector member and secured thereto;

Fig. 4 is an end elevation view partly in section taken on the line 4—4 of Fig. 1;

50 Fig. 5 is a rear view of the socket showing the same connected to the lead wires.

Fig. 6 is a cross sectional view taken on the line 6—6 of Fig. 5 showing the means of connecting the lead wires to the receptacle contacts.

Fig. 7 is a perspective view of the side and 55 bottom contacts of the socket; and

Fig. 8 is a perspective view showing a form of clip that may be used to hold a lamp in contact relation in the socket.

Referring to the drawing in detail, the 60 construction shown comprises a continuous show case lighting fixture made up of a trough like reflector member 1, which may be of any desired length, depending upon the length of the show case in which it is to 65 be used, having a substantially flat top portion 2 and side portions 3 and 4. At intervals along the reflector member 1 openings 5 are cut in the top portion 2 in which are placed rigid sheets of insulating material 6 70 having protruding portions 7 which are secured to the reflector member 1 by riveting or any other desirable means. Receptacles 8 for receiving the lamp to be used in the fixture are attached to the insulating sheets 75 6 so as to be substantially within the reflector member 1.

The receptacles 8 are so constructed that 80 tubular lamps 9 may be inserted therein by a simple swinging movement. In the present disclosure the receptacles 8 are shown as being double sockets but if it is desirable single sockets may be used. These receptacles comprise an insulating base 10 which 85 has U-shaped side portions forming lamp receiving recesses 11 constructed so as to be slightly wider than the base of the lamps to be inserted therein and having tapering inserting entrances 12 so that a lamp may be

placed in the position shown by the dotted lines in Fig. 2 and then inserted in contact position in the recess by merely swinging the bulb end of the lamp upward. The lamp is then held in place by means of spring clips 13 which are attached to the reflector member 1 by riveting or any other means 90 95 that may be desired.

The receptacle 8 has side and end contacts adapted to engage respectively the side and bottom contacts of the lamp to be inserted 100

therein. These contacts are shaped as shown in Fig. 7 being formed from strips of conducting material. The side contact 14 is adapted to be secured to the insulating base 8 by means of a screw 15 which passes through the aperture 16 which is midway between the ends of the contact 14. This strip 14 is then bent so as to form humps 17 adjacent the opening 16 on each side thereof. The ends of the strip 14 have enlarged portions 18 extending transversely of the strip 14. It is these enlarged portions 18 which come in contact with the side contacts of the lamp. The enlarged portions 18 are formed with bent up end portions 18a so as not to obstruct the insertion of the lamps in the recesses. The humps 17 of the side contact 14 extend slightly above the sides of the insulating base 10 so that when the receptacle 8 is attached to the insulating sheet 6 the insulating sheet presses against these humps thereby forcing the enlarged ends 18 down into the recesses 11. By this means these enlarged portions 18 are always in contact with the sides of the lamp base. The end contact 19 is likewise formed of a strip of conducting material having an opening 20 midway between the ends through which the screw 21 is passed and then threaded into the insulating base 10 so as to hold the strip securely. This strip also has two humps adjacent the opening 20, beyond which it is bent down so as to lie adjacent the bottom of the recess 11 as shown in Figs. 4 and 7. The screws 15 and 21 also serve to connect the lead wires 22 and 23 to the side and end contacts of the receptacle. The insulation on the portions of these wires just above the receptacle is removed and the bared portions of the wires are then bent down to lie on the contacts 14 and 19 between the humps 17 and 24. The screws 15 and 21 are then threaded into the base 10 so that the screw heads hold the bared portions of the wires against the middle portions of the side contact 14 and the end contact 19 respectively.

A trough like casing member 25 having side portions 26a and 26b slightly wider than the side portions 3 and 4 of the reflector 1 is placed over the reflector member 1 so that there is a space between the two at the top. Insulating spacers 26 and 27 having enlarged shoulder portions 28 and 29 serve to hold the casing member 25 in spaced relation to the reflector 1. These insulating spacers 26 and 27 are inserted downwardly in the perforations 30 and 31 of the insulation sheet 6 being held in place by the shoulder portions 28 and 29. The insulating spacing member 26 is threaded to receive a screw 32 which is inserted through an aperture 32a in the insulating base and is then threaded into the lower portion of the spac-

ing member 26, whereby the receptacle 8 is secured to the insulating strip within the reflector 1. A screw 33 is inserted through an opening in the casing 25 and is then threaded into the top portion of the spacing member 26 thus holding the casing 25 in position over the reflector member 1. A wood screw 34 passes upwardly through the apertures 34a in the insulating base 10 and 27a in the insulating spacer 27 and is then screwed into the wood frame of the show case to secure the whole fixture in position within the show case as shown in Fig. 2. Although the screws 32, 33 are here shown as holding the fixture in assembled position and the screw 34 as holding the fixture to the show case it is evident that other means might be used equally well.

A thin strip of insulation 35 is placed over the tops of the spacers 26 and 27 between said spacers and the casing 25. This serves to protect the bared portion of the lead wires from short circuit by contact with the casing 25. The lead wires which form a feed through circuit are placed in the space formed between the top of the reflector 1 and the casing 25. These wires 22 and 23 are bent down through the holes 36 and 37 in the insulation sheets 6 as shown in Figs. 3 and 5 and are then connected to the contacts of the receptacle 8 as previously explained. By means of these insulating sheets 6 and 35 the portions of the lead wires which are bared to contact with the receptacle contacts are fully protected and there is no possibility of a short circuit.

While but a single embodiment of this invention is herein shown and described, it is to be understood that various modifications thereof will be apparent to those skilled in the art without departing from the spirit and scope of this invention, and therefore the latter is to be limited only by the scope of the prior art and the appended claims.

I claim:

1. A show case lighting fixture comprising a troughlike reflector member, an insulating receptacle member secured therein having a horizontally extending portion substantially U-shaped in cross-section forming a recess for receiving the base of a tubular lamp and having contacts for engaging with the contacts of said lamp, said recess being of greater width than the diameter of said lamp base, and having a flared inserting entrance at the rounded side of said recess whereby a lamp may be inserted in said fixture by placing the lamp base in the inserting entrance of said receptacle and swinging the bulb end of said lamp inwardly into said casing.

2. A show case lighting fixture comprising a troughlike reflector member, an insulating receptacle member secured therein having a horizontally extending portion substan-

tially U-shaped in cross-section forming a recess for receiving the base of a tubular lamp and having contacts for engaging with the contacts of said lamp, said recess being 5 of greater width than the diameter of said lamp base, and having a flared inserting entrance at the rounded side of said recess whereby a lamp may be inserted in said fixture by placing the lamp base in the inserting entrance of said receptacle and 10 swinging the bulb end of said lamp upwardly into said reflector, and a spring clip attached to said reflector member adapted to engage the bulb end of said lamp to hold 15 the lamp securely in contact position in said receptacle.

3. A show case lighting fixture comprising a troughlike reflector member, an insulating receptacle member secured therein having a 20 hollow horizontally extending portion open along one side forming a recess for receiving the base of a lamp and having side and bottom contacts adapted to engage respectively the side and end contacts of said lamp, said 25 side contact being resiliently positioned in the open side of said horizontally extending portion so as to press against the base of said lamp and hold the lamp in contact position.

4. A show case lighting fixture comprising 30 a troughlike reflector member, an insulating receptacle member secured therein having a horizontally extending portion substantially U-shaped in cross-section forming a recess the rounded side of said 35 portion being flared so as to permit the insertion of a lamp by a simple swinging movement, said receptacle having side and bottom contacts adapted to engage respectively the side and end contacts of a lamp 40 to be inserted therein, said side contact being resiliently positioned in the open side of said recess so as to press against the base of said lamp and hold the same in contact position.

45 5. A show case lighting fixture comprising a troughlike reflector member, a double receptacle member secured therein having oppositely extending horizontal portions substantially U-shaped in cross-section 50 forming recesses the rounded sides of said portions being flared so as to permit the insertion of lamps by a single swinging movement, said receptacle having side and bottom contacts adapted to engage respectively 55 the side and end contacts of lamps to be inserted therein, said side contacts being formed of a single strip of conducting material having enlarged transversely extending end portions, said enlarged portions being 60 ing resiliently positioned in the open side of said recess so as to press against the base of said lamp and hold the same in contact position, and said bottom contacts being formed of a single strip of conducting material having enlarged transversely extend-

ing portions, said enlarged portions being bent down so as to lie adjacent the bottom of said lamp receiving recesses.

6. A show case lighting fixture comprising 70 a troughlike casing, a troughlike reflector member housed thereby, an insulating member secured in said casing having an unthreaded recess for receiving the base of a lamp and having side and bottom contacts adapted to engage respectively the side and 75 center contacts of said lamp, said first side contact being resiliently positioned in said recess at one side thereof, and said insulating member having an inserting entrance flared on the side remote from the reflector 80 sufficiently to enable the lamp to swing outwardly when fully inserted without substantial axial movement whereby a lamp may be inserted therein by placing the lamp base in the inserting entrance of said insulating 85 member and swinging the bulb end of said lamp inwardly into said casing.

7. A show case lighting fixture comprising 90 a troughlike member, a troughlike reflector member housed thereby, an insulating member secured in said casing having an unthreaded recess for receiving the base of a lamp and having side and bottom contacts adapted to engage respectively the side and center contacts of said lamp, said first 95 side contact being resiliently positioned in said recess at one side thereof, said insulating member having an inserting entrance flared on the side remote from the reflector 100 sufficiently to enable the lamp to swing outwardly when fully inserted without substantial axial movement whereby a lamp may be inserted therein by placing the lamp base in the inserting entrance of said insulating member and swinging the bulb end of said 105 lamp inwardly into said casing, and spring means for engaging the bulb and exerting axial pressure thereon to press the lamp center contact against the receptacle center contact.

In witness whereof, I have hereunto subscribed my name.
